UNITED STATES PATENT OFFICE.

FREDERICK PICKERING WALKER, OF BRAINTREE, ENGLAND, ASSIGNOR TO THE CRITTALL MANUFACTURING COMPANY, LIMITED, OF MANOR WORKS, BRAINTREE, ENGLAND.

WINDOW.

1,216,753.

Specification of Letters Patent. Patented Feb. 20, 1917.

Application filed August 12, 1916. Serial No. 114,645.

To all whom it may concern:

Be it known that I, FREDERICK PICKERING WALKER, a subject of the King of Great Britain, residing at Manor Works, Braintree, in the county of Essex, England, have 5 invented new and useful Improvements in Windows, of which the following is a specification.

This invention relates to improvements 10 in pivoted sliding sashes having pivots which run in channels in the jambs and are secured to the sash bars and having two flanges forming weather strips fixed to each sash bar, the flanges being fixed to opposite 15 sides of the sash bar on different sides of the pivot.

According to this invention the weather 20 strips are in contact with the jambs when the window is shut. Also means are provided to turn the sashes slightly upon the pivots when the window is opened. Preferably the pivot is a cone and the sash is 25 secured to it by a spring friction device. The action of shutting the window contracts 30 or extends the spring by the movement of the sash which is in frictional contact with it, and when the window is opened the sash is turned by the extension or contraction 35 of the spring. The result of slightly turning the sashes upon the pivots is that the weather strips are moved out of contact with the sides of the channels in the jambs thereby allowing the sash to slide easily 40 upon the jambs. By this arrangement also the sash is held in any position upon the pivot. The pivots are supported by carriages which have no weather strips but have two pivoted arms which have rollers 45 at their ends engaging with the sides of the channels in the jambs. The arms are connected together by a spring which tends to 50 keep the rollers in contact with the sides of the channels.

Means are provided to hold the weather 55 strips against the sides of the channels in the jambs when the window is closed.

Figure 1 is a side elevation of part of one side of a jamb and Fig. 2 is an elevation partly in section looking from the interior 60 of the room. Fig. 3 is a side elevation of the lower sash slightly opened and drawn to a smaller scale. Fig. 4 is a section on the line 4-4, Fig. 3, and Fig. 5 shows the bottom of the lower sash when closed.

55 The sash bars a, a^1 , of the sashes b, b^1 , are

secured to pivots c, c^1 , free to move in channels d, d^1 , in the jamb e . Flanges f, f^1 , and, g, g^1 acting as weather strips, are fixed to opposite sides of the sash bars a, a^1 , respectively on different sides of the pivots c, c^1 . The pivots c, c^1 , pass through bearings h, h^1 , in the carriages i, i^1 which slide in the channels d, d^1 . The bearings are constantly pressed toward the larger ends of the pivots by springs c^2, c^3 , 60 thus tending to hold the sash in the position into which it is turned. The springs c^2, c^3 , being contracted by the turning of the sash when the window is shut, cause the sashes to turn slightly when the window is 65 opened. On the carriages i, i^1 , are two arms j, j^1 , and k, k^1 , pivoted at l, l^1 and m, m^1 , respectively, and each of the arms has rollers j^2, j^3, k^2, k^3 , at its extremities. The arms j, j^1 are connected together by a spring 70 n and the arms k, k^1 by a spring o which tends to keep the rollers j^2, j^3, k^2, k^3 in contact with the sides of the channels d and d^1 respectively. The carriages i, i^1 are connected together by a chain p which passes 75 over the pulley q , the sashes balancing each other.

On the sill r is a cam piece s which guides the sash into the channel t thus holding the flanges g, g^1 against the sides of the channels d, d^1 .

The flanges on the channels with which the jambs e are provided are of course so formed as to permit the sashes to be properly turned.

The springs c^2, c^3 are so connected with the sashes and with the bearings h, h^1 that when the sashes are in closed position the springs are placed under tension and therefore when the sashes are released in order to be opened the springs cause the sashes to swing or open to a small extent. In this way the weather strips carried by the sashes are withdrawn from the jambs and the raising and lowering of the sashes is facilitated.

The pivots c, c^1 are made conical in order that they may exert a wedging or binding action on the bearings h, h^1 of the carriages i, i^1 , as the bearings are constantly pressed toward the larger ends of the pivots by the springs c^2, c^3 . In this way the sash is held in the position to which it is turned.

What I claim is:—

1. The combination with a window frame having vertical channels in the jambs, of a

sash having sash bars provided with pivots sliding in said channels, and two weather strips fixed to each sash bar one above and the other below the pivot and one of which 5 is on the outside of the sash while the other is on the inside thereof; all of said strips being in contact with the jambs when the window is closed.

2. The combination with a window frame 10 having vertical channels in the jambs, of a sash having sash bars provided with pivots sliding in said channels, and two weather strips fixed to each sash bar one above and the other below the pivot and one of which 15 is on the outside of the sash while the other is on the inside thereof, all of said strips being in contact with the jambs when the window is closed, means for holding the sash in closed position, and devices placed under 20 tension when the sash is closed for turning

the sash on its pivots as soon as the sash is released from the holding means.

3. The combination with a window frame having vertical channels in the jambs, of a sash having sash bars provided with pivots 25 sliding in said channels, two weather strips fixed to each sash bar one above and the other below the pivot and one of which is on the outside of the sash while the other is on the inside thereof, all of said strips being in contact with the jambs when the window is closed, and springs associated with the pivots of the sash which are placed under tension when the sash is closed and which serve to turn the sash slightly on its 30 pivots to withdraw the weather strips of the sash from the jambs and to thus facilitate the raising and lowering of the sash. 35

FREDERICK PICKERING WALKER.
